UNITED STATES PATENT OFFICE.

ARTHUR E. DOWELL, OF WASHINGTON, DISTRICT OF COLUMBIA.

WEB-PRINTING PRESS.

1,348,553.

Specification of Letters Patent.

Patented Aug. 3, 1920.

Application filed November 20, 1918. Serial No. 263,329.

To all whom it may concern:

Be it known that I, ARTHUR E. DOWELL, a citizen of the United States, residing at Washington, District of Columbia, have invented certain new and useful Improvements in Web-Printing Presses; and I hereby declare that the following is a full, clear, and exact description thereof, reference being had to the accompanying drawings, which form part of this specification.

This invention relates to web printing presses and its object is to enable a plurality of say two-plate or page-wide presses to be arranged side by side and operated as a unit, and simultaneously supplied with web from a roll of paper of greater width than each press, say a web four page wide being used and one-half of such web run through each press.

The invention is particularly designed for use with so-called single-page tubular-plate presses of the type shown in Henry F. Bechman's Patent No. 867,230 dated October 1, 1907 in which tubular single-page plates are slipped endwise on or off the plate cylinders from one side of the press. On account of the small diameter of the cylinders in such presses it has not been heretofore found desirable to make such cylinders long enough to carry more than two plates or pages on account of the spring of the cylinders at high speed.

In order to print a four page wide web with such plates presses have heretofore been made with the plate cylinders staggered; sets of such perfecting mechanisms being arranged in zig zag arrangement on opposite sides of the axial line of the press as shown in Bechman's Patent No. 1,240,008 of September 11, 1917; but while such presses will successfully operate upon wide webs they require a great deal of floor space, on account of the peculiar arrangement of the printing mechanisms, but, heretofore, when single-page tubular-plate presses of more than 16 page capacity have been desired this staggered arrangement has been considered the best.

Another object of the present invention is to enable two or more 16 single-page tubular-plate presses, or any two narrow or two page-wide presses, to be arranged close together and operated as one; thus economizing floor space, as compared with the staggered arrangement, and readily operable as one press, while having all their parts

readily accessible and doing away with any special construction of framing and the like, such as is required in the staggered presses.

This invention enables the capacity of a newspaper press room to be enhanced with much less cost to the owners and to utilize the old equipment as part of the new. When two such sixteen-page presses are arranged to be operated in accordance with my invention they can also be operated independently, if desired, to print a narrow web; or simultaneously to print a three or four page wide web, according to the size of paper desired, thus greatly enhancing the flexibility of the product as well as the capacity of the printing office.

While in the present invention a plurality of the narrow web presses are arranged side by side and simultaneously supplied with web from a wide web; each of such presses, if desired, can be independently supplied with web from a narrow web roll; but in that event the present invention would not be employed and its advantages would not be realized, one of which is to dispense with the necessity of handling a large number of narrow web rolls.

I will explain the invention with reference to the accompanying drawings to enable others skilled in the art to adapt and use the same, and in the claims summarize the essential features and combination of parts for which protection is desired.

In said drawings:

Figure 1 is a diagrammatical conventional top plan view of two two-page-wide rotary single-page tubular-plate web presses with means for supplying both presses from a wide roll of web.

Fig. 2 is a front end elevation of Fig. 1.

Fig. 3 is a view similar to Fig. 1 showing a slight modification of the invention.

As indicated in Fig. 1 I arrange two rotary single-page tubular-plate web printing presses A, A, side by side. Preferably each press is constructed as shown and described in Patent No. 979,919 granted Henry F. Bechman, December 27, 1910; each having one or more decks of web perfecting mechanisms, the plate cylinders P in each perfecting mechanism therein being but two pages long, and adapted to carry two single-page tubular-plates arranged end to end and slipped endwise on and off the cylinders over one journal bearing thereof, and each plate cylinder coacting with its related im-

pression cylinder 1, all as explained in the aforesaid patents. Such presses being now well known in the art need no further detailed description herein.

5 Each press A is adapted to print only a two-page-wide web, and a sixteen page press of this type has two superposed decks of printing mechanism each containing two perfecting mechanisms, and a two page wide web is led to each printing mechanism in each deck to be printed thereby and thereafter assembled at a common folder.

As indicated in Fig. 1 the two presses A, A may be driven from a common shaft, or 15 have their driving shafts connected together by a suitable detachable connection, indicated at B, so that said two presses can be driven in unison; or they may be disconnected in case it is desired to operate only 20 one of them; such disconnectible drive may be of any suitable well known kind and does not require detailed illustration or explanation.

Preferably I would arrange the presses 25 A, A so that the gear sides of the presses are adjacent each other, the gearing G thus coming between the presses, as indicated, so that it can readily be housed, if desired, and the operatives will not be endangered by 30 the gearing.

Adjacent one end of the presses I provide supports R (of any suitable kind) for a four-page-wide web W; the shaft of which roll is arranged parallel with the shafts of the 35 plate cylinders P in the presses; and the web may be unwound from the roll during the operation of the press, by any of the usual well known mechanisms (not shown).

After passing from the web roll but before 40 reaching the presses the web is divided by a slitter S; which may be constructed and operated in the usual well known manner, and each half w of the web may then be passed under and over angularly disposed 45 pairs of bars or rollers C and D by which the halves of the web are deflected laterally and separated a distance corresponding to the distance between the ends of the alined plate cylinders P, P in the adjacent presses; 50 and in this way each half web w is brought into alinement with one of the presses.

From the bars or rollers D each half web is led to and through one of the perfecting mechanisms in the alined press, and is operated upon in such press just the same as a 55 single narrow web would have been operated upon if fed to such press from a two-page-wide web roll in the manner described in said Patent No. 867,230. After passing 60 through such presses the half webs may be turned over proper angle bars Z and directed to either folder F of any desired construction, adjacent the delivery ends of the presses and assembled and folded in the well 65 known manner.

Instead of deflecting both halves of the web it would be possible to so locate the four-page-wide roll, as indicated in Fig. 3, that one-half of the web could be led straight or directly from the roll into one of the 70 parallel presses A; while the other half of such web would be deflected sufficiently (by increasing the angle of the deflecting bars or rollers, as indicated at C' and D') to bring the deflected half of the web parallel 75 with the other half of the web and sufficiently spaced therefrom to enable it to be led directly from the deflector D' into and through the other press A as indicated in Fig. 3. 80

In using this invention the presses A, A must be operated synchronously and the web fed uniformly to both presses from the wide web roll, the result then being the same as if the plate cylinders of the presses were 85 four-page-wide.

It will be understood that with this invention there should be as many web rolls as there are pairs of perfecting mechanisms in the two presses. In the drawings I have 90 simply indicated one web roll supplying web to one perfecting mechanism in each press.

If it be desired to use only one press, they can be readily disconnected, and either one 95 operated alone. And if one of the presses should be put out of commission by accident the other section can still be operated to print narrow webs while the injured section is being repaired. 100

This invention renders it a simple matter to increase the capacity of a press room by installing a second or duplicate press, or perfecting unit of a press, beside a previously installed press. For example, if a 105 newspaper had a sixteen-page two-plate-wide press installed, and it was desired to increase its capacity to thirty-two pages, it would not be necessary to replace its sixteen-page press by a specially constructed thirty-two-page press, but instead a duplicate sixteen-page press could be arranged beside the other and suitable web roll supports and deflectors provided, as above described, thus producing a thirty-two page outfit; utilizing 110 therein all the old equipment, but increasing the total page capacity to thirty-two pages with little expense and delay as compared with the installation of a new thirty-two-page press. 115

Uniform tension on the sections of the web fed to the two presses can be readily obtained, if desired, by introducing suitable adjustable tension rollers, indicated at T, between the deflectors and the presses; such 120 adjustable rollers being well known need no particular description or illustration.

What I claim is:

1. In printing apparatus of the character specified, the combination of two rotary 130

web printing presses arranged side by side; with means for supporting a wide roll of web adjacent one end of the presses, the axis of the web roll being parallel with the 5 axes of the cylinders of the presses; means for slitting the web between the web roll and the presses; and means for separating the sections of the web while maintaining the same general direction of movement 10 thereof away from the web roll and directing them to the printing mechanisms to be printed thereby.

2. In printing apparatus of the character specified, the combination of two rotary web printing presses arranged side by side; with means for supporting a roll of web of greater width than the length of the cylinders in either press adjacent one end of the presses so that the axis of the web roll is 20 parallel with the axes of the plate cylinders of the presses; means for slitting the wide web between the web roll and the presses; and means for separating the sections of the web a distance corresponding to the 25 separation of the presses while maintaining the same general direction of movement thereof away from the web roll, and directing the respective section of the web to the respective printing presses to be printed 30 thereby.

3. In printing apparatus of the character specified, the combination of two rotary web printing presses arranged side by side with the gear side of each press adjacent the gear 35 side of the other press; with means for supporting a wide roll of web with its axis parallel with the axes of the cylinders of the presses; means for slitting the web between the roll and the presses; and means 40 for deflecting the sections of the web so as to separate same a distance corresponding to the separation of the presses, the respective sections of the web being directed to the respective printing mechanisms to be 45 printed thereby.

4. In combination a plurality of two-page-wide rotary web printing presses arranged side by side; means for supporting a wide roll of web adjacent one end of such 50 presses, the axis of the web roll being parallel with the axes of the cylinders in the

presses; means for slitting the web between the web roll and the presses; and means for separating the sections of the web while maintaining the same general direction of 55 movement thereof away from the web roll and directing them to the printing mechanisms to be printed thereby; with folding mechanism, adjacent the ends of the presses opposite the web roll, by which the several 60 printed sections of the web are folded.

5. In printing apparatus of the character specified, the combination of two rotary web printing presses arranged side by side with their cylinders in axial parallelism; means 65 for supporting a wide web roll adjacent one end of the presses with the axis of the web roll parallel with the axes of the cylinders; means for slitting a wide web between the web roll and the presses; and means for 70 separating the sections of the web while maintaining the same general direction of movement thereof away from the web roll and directing the respective sections of the web to the respective printing presses to be 75 printed thereby; with folding mechanism located at the end of the presses opposite the web roll; and means for directing the several printed sections of the web to such 80 folding mechanism.

6. In combination two two-page-wide single-page-tubular-plate rotary web printing presses arranged side by side with the gear side of each press adjacent the gear side of the other press; means for supporting a wide roll of web at one end of such 85 presses with the axis of the web roll parallel with the axes of the cylinders; means for slitting the web between the roll and the presses; and means for deflecting the sec- 90 tions of the web so as to separate same a distance corresponding to the separation of the presses, the respective sections of the web being directed to the respective printing mechanisms to be printed thereby; with a 95 folding mechanism adjacent the ends of the presses opposite the web roll; and means for directing the several printed sections of the web to such folding mechanism.

In testimony that I claim the foregoing 100 as my own, I affix my signature.

ARTHUR E. DOWELL.
